UNITED STATES PATENT OFFICE.

WILLIAM A. BERNARD, OF NEW HAVEN, CONNECTICUT, ASSIGNOR TO THE WILLIAM SCHOLLHORN COMPANY, OF NEW HAVEN, CONNECTICUT.

HAND TOOL.

Application filed January 31, 1921. Serial No. 441,330.

This invention relates to hand tools, and more particularly to a tool of this type provided with parallel operating jaws. I have chosen to show a preferred embodiment of my invention as applied to a tool for crimping metal tips upon the ends of shoe-laces, although it will be obvious that the principles of my invention may be applied to similar tools usable for various purposes and provided with operating jaws of various shapes.

One object of my invention is to provide a simple and inexpensive hand tool of the character described, which will be convenient of manipulation and efficient in its operation.

Another object of the invention is to provide improved means for connecting the jaws of the tool to the handles and to further provide improved means for guiding the jaws in their operative movements so that they will be maintained in substantial parallelism.

A still further object of the invention is to provide an improved and simple means for connecting the jaws of the tool to the handles so that they will be maintained in the proper lateral relation to each other.

A still further object of the invention is to provide jaws of a hand tool of the character described with a plurality of cooperating operating surfaces, which may be used for various purposes.

To these and other ends the invention consists in the novel features and combinations of parts to be hereinafter described and claimed.

In the accompanying drawings:

Fig. 1 is a side elevational view of a hand tool embodying the principles of my invention;

Fig. 2 is a view similar to Fig. 1, but showing the tool in its closed position;

Fig. 3 is a front view of the jaws of the structure shown in Fig. 1;

Fig. 4 is a sectional view taken on line 4-4 of Fig. 1;

Fig. 5 is a sectional view taken on line 5-5 of Fig. 1;

Fig. 6 is a sectional view taken on line 6-6 of Fig. 2; and

Fig. 7 is a view showing the various steps

in the operation of crimping the tip about a lace.

While as stated, I have chosen to show in the drawings and to describe with particularity a preferred form of my invention as applied to a tool for crimping the metal tips upon the ends of laces for shoes or the like, it will be obvious that the particular use to which the tool is adapted will depend merely upon the shape of the jaws and upon the working surfaces with which the jaws are provided. The principles of the invention will be readily adaptable to working jaws which are designed for various uses and are not restricted to the precise form shown.

The tool shown is provided with the lever handles 10 and 11, which are preferably made of sheet metal or the like and are U-shaped in cross-section to provide a firm gripping surface for the hands of the operator. These lever handles may be knurled, as shown in Fig. 1, if desired. The handles are bifurcated at their forward ends to form the forked arms 12 upon the lever handle 10 and the forked arms 13 upon the lever handle 11. As shown more particularly in Fig. 4, it will be seen that one of the forked portions of each of the levers is positioned between the two forked portions of the other lever and these two lever handles are pivoted together by the pivot pin 14. A coil spring 15 is wound about the pivot pin 14 between the bifurcated portions of the lever handles and the ends of this spring react against the levers so as to urge the same to open position. The forked portions of the levers extend forwardly in advance of the pivot 14, the two outside forked ends being so curved that the forked ends of one lever will lie in substantial vertical alignment with the ends of the other lever, as shown in Figs. 3, 5 and 6.

The jaws which I have shown connected to the levers are designed for substantially parallel movement in a direction transverse to the longitudinal axis of the tool. These jaws are designated by the numerals 16 and 17, respectively, and consist of two flat members which are mounted for sliding movement on each other to bring their cooperating surfaces into working relation. The jaws

are provided, respectively, with perforations 18 and 19, through which are passed pins 22 and 23, thus pivotally connecting the jaws to lever handles 10 and 11. As illustrated in the drawings, the jaws 16 and 17 are extended longitudinally with respect to the axis of the tool both forwardly and rearwardly beyond their pivotal connection with the handles 10 and 11, whereby when the tool is in operation twisting strains are obviated to a comparatively large extent. As such a pivotal connection alone would allow the jaws to swing freely about these pivot pins, it is necessary to provide means for guiding the jaws in their movements. A preferred method of guiding the jaws is by providing them with cooperating slots and pins to cause them to move in substantial parallelism. While pins, other than the pivot pins may be provided upon the jaws and used for this purpose, I have chosen to illustrate guide slots 20 and 21, in the jaws 16 and 17, formed in transverse alignment with and adapted to receive, respectively, the pivot pins 23 and 22, each of which passes through the perforation in one jaw and the slot in the other jaw, so that common means are provided to pivot the jaws to the handles and to guide them in their movements. The jaws are thus guided in substantial parallelism by the cooperating slots and pins, while the forked ends of the levers, which embrace the jaws upon each side will maintain them in lateral contact with each other.

Each one of the jaws is provided at one end with a returned portion 24, which is turned up to provide a seat 25, which is longitudinally directed with respect to the axis of the tool, while the opposite end of each jaw is provided with a concave surfaced forming edge 26 which is longitudinally directed with respect to the axis of the tool and is designed to cooperate with the seat or socket 25. The returned portion 24 causes the jaws to be shaped in the form of a J in longitudinal cross-section. It will, therefore, be noted that each jaw may be identical with the other in shape, location of slots and perforations, and cutting notches thereby decreasing the cost of manufacture, by requiring but one set of tools for making same, and that larger quantities may be made at one time. As shown in Fig. 5, the jaws when opened will occupy such a position relatively to each other that a substantial opening 27 will be provided above the sockets 25 to permit the insertion of the lace tip therethrough. The jaws may be provided, if desired, at the front edges thereof, with cooperating cutting surfaces 28 and 29, which may be used in connection with the tool described to sever the ends of the laces. A hook or latch 10^a may be provided to hold the handle levers in closed position.

In Fig. 7 is shown various steps in the operation of crimping a metal tip upon the end of a lace 31. The tips are usually sold in the form shown at 30 in this figure in which they are shown as partially rounded 70 to present a U-shaped cross-section.

The operation of the device is as follows: A lace is inserted within a tip, as shown in the view at the left of Fig. 7, and the lace and tip are then inserted through the opening 27 into the socket or seat formed at the end of one of the jaws. The jaws are then brought together, as shown in Fig. 6, and the resulting operation will be the turning of the tip into the form shown in the two views at the right of Fig. 7 and the crimping or binding of the tip in this position. The socket 25 upon one of the jaws may be smaller than that provided upon the other jaw so as to provide for the crimping of 85 larger or smaller tips upon the laces.

In some cases the laces will be found to be longer than desired, and if this is true, they can be cut off to the desired length by the cutting jaws 28 and 29, which are provided at the forward faces of the two jaws. 90

While I have shown and described a preferred embodiment of my invention, in connection with a practical use for the same, it is to be understood that the same is not limited to the exact form and use described in all of its details, as various modifications and variations are possible which will lie within the spirit of the invention and the scope of the appended claims. 100

Another practical use for such a hand tool without alteration thereof is the crimping of a similarly formed metallic tip about a stranded electrical conductor in order to armor the same and protect the strands 105 against the action of a clamp screw. A very effective and strong terminal is formed upon the stranded wire when this tool is used to crimp such a tip about the strands, which obviates, due to the close electrical contact obtained, the use of solder or the like. 110

What I claim is:

1. In a hand tool, a pair of operating handles, a pair of jaws respectively pivoted thereto to be operated thereby, each of said jaws having a looped portion to receive an edge portion of the other jaw. 115
2. In a hand tool, a pair of operating handles, a pair of jaws respectively pivoted thereto to be operated thereby, each of said jaws being reversely looped to form a seat and being provided with an operating edge arranged to enter and be withdrawn from the seat in the other jaw. 120
3. In a hand tool, a pair of operating handles, jaws respectively connected thereto to be operated thereby, each of said jaws being reversely looped to form a seat and being provided with an operating edge arranged to enter and be withdrawn from the 125
- 130

seat in the other jaw, said edges normally being withdrawn from said seat in the other jaw to permit entrance of the work therein.

4. In a hand tool, a pair of operating handles, overlapping jaws pivoted thereto for operation thereby, said jaws being slideable on each other in their operative movement, and each having one end returned in the direction of the other to form an open seat, and the other ends of said jaws being adapted to cooperate respectively with said seats.

5. In a hand tool for attaching shoe lace tips or the like, a pair of handles having a pair of jaws pivoted thereto for operation thereby, said jaws being substantially of a J shape in longitudinal cross section, and being mounted one upon the other, whereby the hook end of each jaw engages a portion of the other jaw when said jaws are in a closed position.

6. In a hand tool, a pair of jaws, each jaw having a hooked portion forming a seat which is longitudinally disposed with respect to the axis of the tool, and an edge portion longitudinally directed with respect to the axis of the tool, said jaws being mounted one upon the other in such a manner that the edge portion of one will be engaged by the hooked portion of the other when the jaws are in closed position.

7. In a hand tool, a pair of handles, a pair of jaws pivotally connected to said handles for operation thereby, each jaw having a hooked portion and an edge portion longitudinally directed with respect to the axis of the tool, said hooked portion and said edge portion being substantially identically located in each jaw, said jaws being so mounted upon each other that the edge portion of one will be engaged by the hooked portion of the other when the jaws are in closed position, and will be entirely disengaged when the jaws are in open position.

8. In a hand tool for crimping shoe lace tips or the like, a pair of handles, a pair of jaws pivotally connected to said handles for operation thereby, each jaw having a hooked portion and an edge portion longitudinally directed with respect to the axis of the tool, said jaws being so mounted upon each other that the edge portion of one will be engaged by the hooked portion of the other when the jaws are in closed position, one of the cooperating hook and edge portions being adapted to receive and crimp tips of a different size than the other cooperating hook and edge portions.

9. A hand tool comprising a pair of pivoted handles, a pair of jaws pivotally connected thereto and extending transversely thereof and adapted to slide on each other in their operative movement, the opposite ends of each of said jaws being provided with cooperating working surfaces.

10. In a hand tool, a pair of pivoted operating handles, a pair of jaws connected thereto and extending transversely thereof, the opposing ends of each jaw being adapted to cooperate to crimp an article therebetween, and pivot pins connecting said jaws with said handles, each pivot pin passing through both of said jaws.

11. In a hand tool, a pair of jaws, each comprising a flat member having a returned portion at one end to provide a seat and a forming edge surface upon the other end, and means to move said jaws toward each other, said jaws being arranged to cause the forming edge surface on the end of each to cooperate with the seat in the other.

12. In a hand tool, a pair of jaws, each comprising a flat member having a returned portion at one end to provide a seat and a forming edge surface upon the other end, and means to move said jaws toward each other, said jaws being mounted to slide one upon the other, and arranged to cause the forming edge surface on the end of each to cooperate with the seat in the other.

13. A hand tool for the purpose described, including a pair of jaws slideable one upon the other, one jaw being provided with a crimping seat portion extending the entire width at one end thereof, and a crimping surface portion extending the entire width at the other end thereof, said portions being adapted to cooperate respectively with the crimping surface portion extending the entire width at one end, and a crimping seat portion extending the entire width at the other end of the other jaw, and means to slide one jaw upon the other into closed and opened positions.

14. In a hand tool, a pair of handle members pivoted together intermediate their ends, a pair of jaws disposed in parallelism with the longitudinal axis of the tool, and pivoted respectively to said handle members at one end thereof, said jaws extending longitudinally forwardly and rearwardly beyond their pivotal connection with said handle members.

15. In a hand tool, a pair of handle members, a pair of jaw members pivoted respectively one to each handle member at one end thereof, each of said jaw members comprising a flat member having a returned portion at one end thereof, and a forming end edge surface at the other end thereof, said returned portion of one jaw cooperating with the forming end edge surface of the other, the returned portion and the forming end edge surface of each jaw being disposed substantially in parallelism with the longitudinal axis of the tool.

16. In a hand tool, a pair of handle members, a pair of jaw members pivoted respectively one to each handle member at one end thereof, each of said jaw members compris-

ing a flat member having a returned portion at one end thereof, and a forming end edge surface at the other end thereof, said returned portion of one jaw cooperating with the forming end edge surface of the other, the returned portion and the forming end edge surface of each jaw being disposed substantially in parallelism with the longitudi-

nal axis of the tool and extending longitudinally forwardly and rearwardly beyond the 10 pivotal connection of said jaw members with said handle members.

In witness whereof, I have hereunto set my hand on the 29 day of January, 1921.

WILLIAM A. BERNARD.
